[57] CLAIM

The ornamental design for a display board for memorabilia, as shown and described.

DESCRIPTION

FIG. 1 is a front elevational view of a display board for memorabilia showing my new design, with the rear being flat and unornamented;

FIG. 2 is a right side elevational view thereof, with the opposite side being a mirror image;

FIG. 3 is a front elevational view of a second embodiment thereof, with the rear being flat and unornamented;

FIG. 4 is a right side elevational view thereof, with the opposite side being a mirror image; and,

FIG. 5 is a front elevational view of the first embodiment, with the broken line showing for illustrative purposes only and forming no part of the claimed design.
